(57) **CLAIM**

The ornamental design for a flashlight, as shown and described.

DESCRIPTION

FIG. 1 is a front view of a first embodiment of our design; FIG. 2 is a back view thereof;

FIG. 3 is a left side view thereof;

FIG. 4 is a right side view thereof;

FIG. 5 is a bottom view thereof;

FIG. 6 is a front view of a second embodiment of our design;

FIG. 7 is a back view thereof;

FIG. 8 is a left side view thereof;

FIG. 9 is a right side view thereof;

FIG. 10 is a bottom view thereof;

FIG. 11 is a front view of a third embodiment of our design;

FIG. 12 is a back view thereof;

FIG. 13 is a left side view thereof;

FIG. 14 is a right side view thereof;

FIG. 15 is a bottom view thereof;

FIG. 16 is a front view of a fourth embodiment of our design;

FIG. 17 is a back view thereof;

FIG. 18 is a left side view thereof;

FIG. 19 is a right side view thereof;

FIG. 20 is a bottom view thereof;

FIG. 21 is a front view of a fifth embodiment of our design;

FIG. 22 is a back view thereof;

FIG. 23 is a left side view thereof;

FIG. 24 is a right side view thereof; and,

FIG. 25 is a bottom view thereof.

The dashed lines in the figures form no part of the claimed design.

1 Claim, 15 Drawing Sheets
